ABSTRACT

Piezoelectric ceramic compositions are provided which are characterized by high stability with temperature and time in resonant frequency and by high electromechanical coupling coefficients and high dielectric constants or by high electromechanical coupling coefficients and high mechanical quality factors. These ceramic compositions are ternary systems, in solid solution form, of the type formula

Optimal ternary compounds are within the area ABCD of Fig. 2 of the accompanying drawings; very best compounds are defined by ABE. An especially good material consists of the solid solution of the formula

PIEZOELECTRIC CERAMIC COMPOSITIONS

This invention relates to piezoelectric ceramic compositions and articles of manufacture fabricated therefrom. More particularly, the invention pertains to novel ferroelectric ceramics which are polycrystalline aggregates of certain constituents. These piezoelectric compositions are sintered to ceramics by ordinary ceramic techniques and thereafter the ceramics are polarized by applying a DC voltage between the electrodes to impart thereto electromechanical transducing properties similar to the well-known piezoelectric effect. The invention also encompasses the calcined product of the raw ingredients, and the articles of manufacture such as electromechanical transducers fabricated from the sintered ceramics.

The ceramic bodies embodied by the present invention exist basically as a solid solution comprising the ternary system

The use of piezoelectric materials in various transducer applications in the production, measurement and sensing of sound, shock, vibration, pressure, etc., has increased greatly in recent years. Both crystal and ceramic types of transducers have been widely used. But because of their potentially lower cost and facility in the fabrication of ceramics with various shapes and sizes and their greater durability for high temperature and/or for humidity than that of crystalline substances such as Rochelle salt, piezoelectric ceramics materials have recently gained importance in various transducer applications.

The piezoelectric characteristics of ceramic required in various chemical applications vary with the particular kind of application. For example, electromechanical transducers such as phonograph pickups and microphones require piezoelectric ceramics characterized by a substantially high electrochemical coupling coefficient and dielectric constant. On the other hand, it is desired in filter applications of piezoelectric ceramics that the material exhibits a higher value of mechanical quality factor and high electromechanical coupling coefficient. Furthermore, ceramic materials require a high stability with temperature and time in resonant frequency and in other electrical properties.

As more promising ceramics for these requirements, lead titanate-lead zirconate has been in wide use up to now. However, it is difficult to get a very high mechanical quality factor along with high planar coupling coefficient in the lead titanate-lead zirconate ceramics. Moreover, the dielectric and piezoelectric properties of the lead titanate-lead zirconate ceramics change greatly with firing technique due to evaporation of PbO.

It is, therefore, the fundamental object of the present invention to provide novel and improved piezoelectric ceramic materials which overcome at least one of the problems outlined above. A more specific object of the invention is to provide improved polycrystalline ceramics characterized by very high mechanical quality factor along with high piezoelectric coupling coefficient.

Another object of the invention is the provision of novel piezoelectric ceramic compositions, certain properties of which can be adjusted to suit various applications.

A further object of the invention is the provision of improved electromechanical transducers utilizing, as the active elements, electrostatically polarized bodies of the novel ceramic compositions.

These objects of the invention and the manner of their attainment will be readily apparent from a reading of the following description and from the accompanying drawings, in which:

FIG. 1 is a cross-sectional view of an electromechanical transducer embodying the present invention.

FIG. 2 is a triangular compositional diagram of materials utilized in the present invention.

Before proceeding with a detailed description of the piezoelectric materials contemplated by the invention, their illustrated application in electromechanical transducers will be described with reference to FIG. 1 of the drawings wherein reference character 7 designates, as a whole, an elec-

tromechanical transducer having, as its active element, a preferably disc-shaped body 1 of piezoelectric ceramic material according to the present invention.

Body 1 is electrostatically polarized, in a manner hereinafter set forth, and is provided with a pair of electrodes 2 and 3, applied in a suitable and per se conventional manner, on two opposed surfaces thereof. Wire leads 5 and 6 are attached conductively to the electrodes 2 and 3 respectively by means of solder 4. When the ceramic is subjected to shock, vibration or other mechanical stress, the generated electrical output can be taken from wire leads 5 and 6. Conversely, as with other piezoelectric transducers, application of electrical voltage to electrodes 5 and 6 will result in mechanism deformation of the ceramic body. It is to be understood that the term electromechanical transducer as used herein is taken in its broadest sense and includes piezoelectric filters, frequency control devices, and the like, and that the invention may also be used and adapted to various other applications requiring materials having dielectric, piezoelectric and/or electrostrictive properties.

According to the present invention, the ceramic body 1, FIG. 1, is formed of a novel piezoelectric composition which is a polycrystalline ceramic composed of

The present invention is based on the discovery that within particular ranges of this ternary system the specimens exhibit a very high mechanical quality factor along with high planar coupling coefficient.

The present invention has various advantages in manufacturing process and in application for ceramic transducers. It has been known that the evaporation of PbO during firing is a problem in sintering of lead compounds such as lead titanate zirconate. The invented composition, however, shows a smaller amount of evaporated PbO than usual lead titanate zirconate does. The ternary system can be fired without any particular control of PbO atmosphere. A well-sintered body of the present composition is obtained by firing in a ceramic crucible with a ceramic cover made of Al_2O_3 ceramics. A high-sintered density is desirable for humidity resistance and high piezoelectric response when the sintered body is applied to a resonator, etc.

All possible compositions coming within the ternary system

are represented by the triangular diagram constituting FIG. 2 of the drawings. Some compositions represented by the diagram, however, do not exhibit high piezoelectricity, and many are electromechanically active only to a slight degree. The present invention is concerned only with those compositions exhibiting piezoelectric response of appreciable magnitude. As a matter of convenience, the planar coupling coefficient (K_p) of test discs will be taken as a measure of piezoelectric activity. Thus, within the area bounded by lines connecting points ABCD, FIG. 2, all compositions polarized and tested showed a planar coupling coefficient of approximately 20 percent or higher. The compositions in the area of the diagram bounded by lines connecting points A, B, and E, FIG. 2, exhibit a planar coupling coefficient of approximately 30 percent or higher. The molar percent of the three components of compositions ABCDE are as follows:

	$\text{Pb}(\text{Mn}_{1/3}\text{Nb}_{2/3})\text{O}_3$	PbTiO_3	PbZrO_3
A	5.0	48.0	47.0
B	25.0	50.0	25.0
C	37.5	37.5	25.0
D	25.0	12.5	62.5
E	25.0	25.0	50.0

Furthermore, the compositions near the morphotropic phase boundary of the ternary system, particularly

give ceramic products having a planar coupling coefficient of 45 percent or higher.

According to the present invention, piezoelectric and dielectric properties of the ceramics can be adjusted to suit various applications by selecting the proper composition.

The composition described herein may be prepared in accordance with various well-known ceramic procedures. A preferred method, however, hereinafter more fully described consists in the use of PbO or Pb_3O_4 , MnO_2 or Mn_3O_4 , Nb_2O_5 , TiO_2 , ZrO_2 .

The starting materials viz, lead oxide (PbO), manganese dioxide (MnO_2), niobia (Nb_2O_5), titania (TiO_2), zirconia (ZrO_2), all of relatively pure grade e.g., C.P. grade are intimately mixed in a rubber-lined ball mill with distilled water. In milling the mixture, care should be exercised to avoid, or the proportions of ingredients varied to compensate for, contamination by wear of the milling ball or stones.

Following this wet milling, the mixture is dried and mixed to assure as homogeneous a mixture as possible. Thereafter, the mixture is suitably formed into a desired form at a pressure of 400 kg./cm.² (kilograms per square centimeter). The obtained compacts are prereacted by calcination at a temperature of around 850° C. for 2 hours.

After calcination, the reacted material is allowed to cool and is then wet milled to a small particle size. Once again, care should be exercised to avoid, or the proportions of ingredients varied to compensate for, contamination by wear of the

thickness of 1 millimeter. The polished disc surfaces may then be coated with silver paint and fired to form silver electrodes, these procedures being carried out in per se conventional manner. Finally, the discs are polarized while immersed in a bath of silicone oil at 100° C. A voltage gradient of DC 4 kv. per mm. is maintained for 1 hour, and the discs are field-cooled to room temperature (15° to 30° C.) in 30 minutes.

The piezoelectric and dielectric properties of the polarized specimens have been measured at 20° C. in a relative humidity of 50 percent and at a frequency of 1 kc. Examples of specific ceramic compositions according to this invention and various pertinent electromechanical and dielectric properties thereof are given in the following table. The composition in which both the mechanical quality factor (Q_M) and planar coupling coefficient show high values are novel compositions. From the table, it will be readily evident that the exemplary compositions selected from the area bounded by lines connecting points ABCD of the diagram of FIG. 2 are characterized by very high mechanical quality factor and high planar coupling coefficient. The composition

shows a high resonant frequency stability with temperature within the range 20° C. to 85° C. The change in resonant frequency is 0.1 percent. These properties are important to the use of piezoelectric compositions in filter applications.

TABLE

Example No.	Mole percent of composition			24 hours after poling		Mechanical quality factor, Q_M
	$\text{Pb}(\text{Mn}_{1/3}\text{Nb}_{2/3})\text{O}_3$	PbTiO_3	PbZrO_3	Dielectric constant, ϵ at 1 kc/s.	Planar coupling coeff., K_p	
1	50.0	25.0	25.0	530	0.059	1,023
2	37.5	37.5	25.0	969	0.205	925
3	25.0	75.0		988		
4	25.0	62.5	12.5	302	0.101	1,184
5	25.0	50.0	25.0	592	0.301	1,581
6	25.0	43.0	32.0	1,032	0.405	1,076
7	25.0	40.0	35.0	869	0.433	799
8	25.0	34.0	41.0	779	0.471	995
9	25.0	31.0	44.0	501	0.348	1,904
10	25.0	25.0	50.0	463	0.310	2,657
11	25.0	12.5	62.5	444	0.212	3,528
12	25.0		75.0	502	0.064	1,646
13	13.0	42.0	45.0	1,157	0.505	929
14	5.0	48.0	47.0	926	0.487	1,076

milling balls or stones. Depending on preference and the shapes desired, the material may be formed into a mix or slip suitable for pressing, slip casting, or extruding, as the case may be, in accordance with per se conventional ceramic procedures. The samples for which data are given hereinafter were prepared by mixing 100 grams of the milled presintered mixture with 5 cc. of distilled water. The mix was then pressed into discs of 20-mm. diameter and 2-mm. thickness at a pressure of 700 kg./cm.². The pressed discs were fired at 1,200°-1,270° C. for 45 minutes. According to the present invention, there is no need to fire the composition in an atmosphere of PbO and no special care is required for the temperature gradient in the furnace, in contrast to the prior art requirements. Thus, according to the present invention, uniform and excellent piezoelectric ceramic products can be easily obtained simply by covering the samples in an alumina crucible during firing.

The sintered ceramics are polished on both surfaces to the

45 From the foregoing table, the values of mechanical quality factor, planar coupling coefficient and dielectric constant can be adjusted to suit various applications by selecting the corresponding composition.

In addition to the superior properties shown above, compositions according to the present invention yield ceramics of good physical quality, which polarize well. It will be understood from the foregoing that the ternary ceramics

form excellent piezoelectric ceramic bodies.

What is claimed is:

1. A piezoelectric ceramic material consisting of the solid solution having the following formula:

2. An electromechanical transducer element comprising an electrostatically polarized solid solution ceramic consisting of a ceramic composition according to claim 1.
